UNITED STATES PATENT OFFICE.

JOHN A. JOHNSON, OF BROOKLYN, NEW YORK.

COMPRESSING AND PACKING MACHINE.

Application filed March 31, 1927. Serial No. 179,764.

This invention relates to means for imparting reciprocatory movement to a slidable member, such as a plunger carrier, and while the invention is particularly adapted to apparatus for packing granulated or comminuted material, such as cork with a binding material, into stick form, it is also applicable to other apparatus, and it is the object of the invention to provide means to impart to a slidable member reciprocatory movement in series of successively decreasing extent, and to provide means for this purpose which is simple in construction and efficient in operation.

In carrying out the invention I have illustrated the same as embodied in apparatus for packing comminuted cork into stick form wherein a tube or series of tubes is positioned by a carrier and support therefor with the opposite ends relative to material carrying pockets to which material is fed from a hopper or hoppers, and from which pockets the material is delivered and packed into opposite ends of a tube or tubes as successive increments by a plunger or plungers mounted in reciprocatory carriers in line with the material carrying pockets, the tube carrier being adapted to be operated after a series of successive movements have been imparted to the plunger carriers and the tube or tubes filled with comminuted material to advance the filled tubes and position further tubes to be filled relative to the material carrying pockets.

In the drawings accompanying and forming a part of this specification Figure 1 is a side elevation, partly in section and partly broken away, of a comminuted cork packing apparatus embodying my invention.

Figure 2 is an end elevation looking at the right of Figure 1.

Figure 3 is a side elevation, on an enlarged scale and partly broken away of the right hand end of the apparatus shown in Figure 1.

Figure 4 is a plan view on an enlarged scale of the right hand end of the apparatus shown in Figure 1.

Figure 5 is a perspective view of the means for imparting reciprocatory movement to the plunger carrier in series of successive decreasing extent.

Figure 6 is a sectional perspective view of a portion of the plunger carrier to show the means for operatively connecting the same with its reciprocating means.

Figure 7 is a perspective view of the means

for imparting reciprocatory movement to the plunger carrier in series of successive decreasing extent.

Figure 8 is an end elevation of means for imparting intermittent rotative movement to the means shown in Figure 7.

Figure 9 is a longitudinal sectional view, partly in section, of the plunger carrier actuating means and plunger carrier in relation thereto, the parts being shown in full lines in position of rest and in dotted lines in advanced position, and showing means mounted on the carrier to co-operate with means operative with the plunger carrier reciprocating means to impart the initial return movement to the plunger carrier.

Figure 10 is a cross sectional view taken on the line 10—10 of Figure 9 looking in the direction of the arrow.

Figure 11 is a longitudinal sectional view of the means shown in Figure 9 with the plunger carrier and its reciprocating means in advanced position and said latter means co-acting with the means to impart the initial return movement to the plunger carrier.

Figure 12 is a perspective view of a lever latch carried by and for connecting the plunger carrier with its reciprocating means to impart the initial return movement thereto.

Figure 13 is a perspective view of a member for releasing the lever latch shown in Figure 12 from the plunger carrier reciprocating means.

I have illustrated my invention in connection with apparatus for packing granulated or comminuted cork mixed with a binder into tubes to form sticks from which disks are sliced to constitute the lining of closure caps for receptacles as described and illustrated in Patent No. 1,477,358 dated December 11, 1923, wherein a series of tubes 14 are supported at the opposite ends by a turret comprising a pair of wheels 15 having recesses disposed about the periphery and mounted in spaced relation upon a rotatable shaft 16, and by means of which support the tubes seated in the peripheral recesses are positioned with the ends in line with pockets 17 arranged in an arc of a circle coinciding with the tube receiving recesses in the turret wheels, said pockets being disposed below hopper outlets 18 to receive material therefrom. The tube support is intermittently rotated from a drive shaft 19 by a pinion (not shown) on said shaft meshing with a gear 20 fixed to a shaft journaled in a bracket 21 fixed to the base of the

framework, a wheel 22 also fixed to said shaft having a section of teeth 23 adapted upon each revolution of said wheel to mesh with a pinion 24 fixed to a shaft journaled in an upwardly extending portion 25 of the bracket 21, the shaft carrying the pinion 24 also having a pinion 26 fixed thereon to mesh with a gear 27, the ratio and timing of the gearing being such so that the tube carrying support 5 will have an intermittent movement imparted thereto to move filled tubes away from the material receiving pockets and position another series of tubes relative to said pockets upon the imparting of a predetermined series 10 of reciprocatory movements to a series of plungers 28 to deliver material from the pockets 17 into the end of the tubes carried by the support. The shaft 19 is driven from a drive shaft 29 by a pinion 30 on said latter shaft 20 meshing with a gear 31 on shaft 19. The drive shaft 29 is driven from a suitable source of power by a belt (not shown) passing around a pulley 32 on said shaft. The plungers 28 are mounted at one end in a carriage 25 or carrier 33 slidably mounted and guided for reciprocatory movement by two pairs of rollers 34, 35 at the opposite ends of the carrier upon rods 36 fixed in the frames, one roller of each pair engaging above and the other 30 roller below the rods. There are two plunger carriers one arranged at the outer side of each series of pockets 14 and as both of said carriers, the mounting and operating means therefor, are the same description one will suffice for both.

The comminuted cork is delivered from the pockets 17 into the tubes by the plungers 28 in successive increments to compensate for the increased quantity of material in the 40 tubes, and means are therefore provided to impart to the plungers movements of successive variable decreasing extent in the delivery movement thereof from a predetermined position of rest and returned to said position. 45 In the embodiment of this means as shown in Figures 1 to 8, inclusive, a cylinder 37 is arranged with stepped faces 38 circularly disposed about and extending longitudinally from one end thereof, which cylinder is in the 50 nature of a stepped cam member, said cylinder being fixed on a sleeve 39 rotatably and slidably mounted on a shaft 40 with the collar 41 mounted upon the reduced end of the cylinder in opposed and spaced relation to the 55 stepped faces 38 and secured thereon by a nut 42 threaded onto the reduced sleeve end. On the opposite reduced end of the cylinder there is fixed a wheel 43 arranged with circumferentially spaced tooth sections 44 with intervening curved faces 45, said wheel constituting one member of Geneva gearing to impart rotative movement to the sleeve and cylinder stepped face distances. The other member 60 of the Geneva gearing is in the form of a wheel disk 46 arranged with tooth section 47

to mesh with the tooth sections of the wheel 43 to impart an intermittent movement to said wheel upon each revolution of the wheel 46, the curved portions 45 intervening between the tooth sections of wheel 43 being 70 of a curvature to coincide with the periphery of the disk 46 and the latter serving to hold the wheel 43 and thereby the cylinder carrying sleeve 39 against rotation. In the present instance the cam sleeve is arranged with 75 ten stepped faces 38 and the Geneva gear 43 is arranged with a corresponding member of tooth section whereby one revolution is imparted to said member and the cylinder carrying sleeve upon each ten revolutions of the 80 Geneva gear member 46, and a series of ten movements in one direction imparted to the plunger carrier of successive variable decreasing extent. The Geneva member 46 is mounted on a rotatable shaft 48 by a spline 85 and keyway whereby it is adapted to rotate with said shaft and have movement longitudinally thereon. The shaft 48 is driven from a shaft 19 by a sprocket chain 49 passing around sprocket wheels 50 and 51 fixed to the 90 respective shafts 48 and 19.

The cylinder carrying sleeve 39 with the Geneva gear 43 is reciprocated upon the shaft by a lever 52 pivotally supported at 53 upon a bracket upon the framework, the opposite 95 end of the lever being bifurcated to straddle the shafts 40 and 48 and connected with the cylinder carrying sleeve 39 by links 54 pivotally connected at one end with the legs of the lever bifurcation and at the opposite end to 100 trunnions 55 extending laterally and diametrically opposite from a collar 56 loosely mounted on the sleeve 39 in interposed relation to the stepped face cylinder 37 and the Geneva gear 43. The lever 52 is oscillated 105 to impart reciprocatory movement of the same extent to the cylinder carrying sleeve 39 by a crank shaft 57 rotatable on an axis transverse to the axes of shafts 40, 48, the lever being connected intermediate its ends with 110 the crank of said shaft by a connecting rod 58. The crank shaft is driven from the shaft 19 by a bevel pinion 59 fixed to said shaft meshing with a bevel gear 60 on shaft 19. The Geneva gear 43 participates in the reciprocatory movement of the cylinder carrying sleeve 39, and to maintain the same in operative connection with the Geneva gear member 46 the latter is connected with the stepped cam cylinder carrying sleeve to participate in the 115 movement thereof by the link member 56 mounted on the hub of the Geneva gear 46, as at 61, in interposed relation to the gear and the collar 62 fixed to the hub of said gear. The reciprocatory movement of the sleeve 39 120 is transmitted to the plunger carrier 33 by an abutment 63 fixed to and extending laterally from the plunger carrier interposed to the collar 41 and the stepped faces of the cylinder 37. The plunger cam is moved in one direc- 125 130

tion to a predetermined position of rest by the collar 41 engaging at one side of said abutment 63, and movement in the opposite direction is imparted to the plunger carrier by 5 the movement of the stepped faces 38 with the opposite side of said abutment in the levers movement of the cylinder carrying sleeve. The Geneva gear is so timed that there will be a rotative movement imparted to the 10 stepped cam cylinder a stepped face distance upon each reciprocation of said cam cylinder and whereby there will be imparted to the plunger carrier the successive movements of variable extent by the engagement of the successive stepped faces of the cam cylinder 15 with the abutment 63.

It will be obvious that various modifications may be made in construction and arrangement of parts, and that portions of the 20 invention may be used without others and come within the scope of the invention.

Having thus described my invention I claim:

1. The combination of a slidable plunger 25 carrier, a rotatable and reciprocatory member arranged with circularly disposed stepped faces, an oscillatory lever to reciprocate said member, and means to rotate said member one stepped face distance upon each reciprocatory movement thereof, said stepped face member being arranged with means to co-operate with the plunger carrier to move the same to a predetermined position in one direction, and the stepped faces of said member 30 adapted to successively co-operate with the plunger carrier to move the same distances of successive variable extent in the opposite direction.

2. The combination of a slidably mounted 40 plunger carrier, and means to impart movement of successive variable extent to said carrier in one direction from a position of rest, comprising a rotatable and reciprocatory member arranged with circularly disposed stepped faces adapted for successive connection with the plunger carrier in the movement of said member in one direction and transmit said movement to the carrier, and said member arranged with means to 45 connect said member with and transmit the return movement thereof to and return the carrier to position of rest, and means to rotate said member a stepped face distance upon each reciprocation thereof.

55 3. Plunger carrier reciprocating means as claimed in claim 2, wherein the stepped face member comprises a cylinder with the stepped faces disposed longitudinally thereof and mounted to have movement in the plane of movement of plunger carrier.

4. Plunger carrier reciprocating means as claimed in claim 2, wherein the stepped face member comprises a cylinder with the stepped faces disposed longitudinally thereof and mounted to have movement in the plane of

movement of the plunger carrier, a mounting sleeve on which the cylinder is fixed, a collar fixed on the sleeve in opposed and spaced relation to the stepped faces of the cylinder, and an abutment fixed to the plunger carrier interposed between the stepped faces of the cylinder and collar and adapted for engagement therewith to connect and transmit the reciprocatory movement of the cylinder to the carrier. 70

5. In plunger carrier reciprocating means as claimed in claim 2, an oscillatory lever having a pivotal link connection with the stepped face member and operative to reciprocate the latter and means to oscillate the 75 lever.

6. Plunger carrier reciprocating means as claimed in claim 2, wherein the means to rotate the stepped face member comprises a Geneva gearing, one member of which is 85 connected with the stepped face member and the other member mounted on a driver to rotate therewith and have axial movement thereon, and means to connect said latter Geneva gear member with the stepped face 90 member to transmit the reciprocatory movement thereof to said Geneva gear member and maintain the same in operative connection with the Geneva gear member connected to the stepped facing member. 95

7. Plunger carrier reciprocating means as claimed in claim 2, wherein the means to rotate the stepped face member comprises a wheel fixed to said member to participate in the rotative and reciprocatory movement 100 thereof, said wheel having circumferentially spaced, toothed and intervening curved sections, a second wheel having a toothed section adapted to mesh upon successive revolutions thereof with the successive tooth section of the first wheel, and the plane peripheral portion of said second wheel to ride over the curved sections of the first wheel and hold said latter while against rotative movement, a drive shaft upon which said second 110 wheel is mounted to rotate with and have sliding movement on said shaft, and means to connect said second wheel with the stepped face member to transmit the reciprocatory movement of the latter to said second wheel 115 and maintain the same in operative connection with the first wheel.

8. In plunger carrier reciprocating means as claimed in claim 2, an oscillatory lever, a pivotal link connection between said lever 120 and the stepped face member, a rotatable crank shaft, and a rod to connect the lever with the crank of said shaft to oscillate the lever from the rotation of the crank shaft.

9. In apparatus for packing comminuted 125 cork into stick form, the combination with spaced and aligned material carrying pockets, an intermittently rotatable support for a tube adapted to position the opposite ends of a tube in alignment with the pockets, a pair of 130

- slidably mounted plunger carriers operative to actuate plungers carried thereby to deliver the material from the pockets to opposite ends of a tube supported in alinement therewith, and means to impart a series of material feeding movements of successive variable extent to the plunger carriers, comprising a pair of members arranged with circularly disposed stepped faces mounted to have rotative and reciprocatory movement in the plane of movement of the plunger carrier, means to reciprocate and impart intermittent rotative movement of stepped face distances to said members upon each reciprocatory movement thereof, and means to actuate the tube support to position another tube relative to the material carrying pockets after each successive series of movements of variable extent have been imparted to the plunger carrier.
10. Apparatus for packing comminuted cork into stick form as claimed in claim 9, wherein the members with the stepped faces comprise cylinders fixed to sleeves, a collar fixed to said sleeves to impart return movement to the carriers, Geneva gearing to impart rotative movement of stepped face distances to said sleeves and cylinders, and means to impart reciprocatory movement to said sleeves and cylinders.
11. The combination of a slideable plunger carrier, a cylinder supported to have rotative and reciprocatory movement arranged with circumferentially disposed stepped faces, said cylinder being adapted for connection with the carrier during the movement thereof in one direction to move the plunger to a predetermined position, and the stepped faces successively brought into operative connection with the plunger carrier when moved in the opposite direction to impart movement of successive variable extent to the plunger carrier, an oscillatory lever having a link connection with the cylinder to impart reciprocatory movement thereto of predetermined extent, and means to intermittently rotate the cylinder one stepped face distance upon each reciprocation thereof.
12. The combination with a slideably mounted plunger carrier, of means to impart reciprocatory movements thereto in series of successively decreasing extent embodying a rotatable and reciprocatory cam member arranged with stepped faces for successive engagement with the carrier in the reciprocatory movement of the cam in one direction, means reciprocatory with the cam for engagement with the carrier to impart return movement thereto in the reciprocatory movement of the cam in the opposite direction, and means to reciprocate the cam and impart intermittent rotative movement thereto upon each reciprocatory movement thereof.
13. Means for imparting reciprocating movement to a plunger carrier as claimed in claim 12, wherein the cam member comprises a cylinder having the stepped faces disposed circumferentially about and longitudinally thereof, said cylinder being mounted on a slideable and rotatable sleeve and the sleeve carrying the means to impart the return movement to the plunger carrier.
14. Means for imparting reciprocatory movements to a plunger carrier as claimed in claim 12, wherein the stepped faces of the cam member are circumferentially and radially disposed about the same.

Signed at the city of New York, in the county of New York and State of New York, this 17th day of March, 1927.

JOHN A. JOHNSON.
